FLEXIBLE CONNECTOR

Warren G. Taylor, Essex Fells, and Charles L. Baxter, West Caldwell, N. J., assignors to Federal Telephone and Radio Corporation, New York, N. Y., a corporation of Delaware

Application April 6, 1946, Serial No. 660,102

12 Claims. (Cl. 250—27.5)

1

This invention relates to electron discharge devices and particularly to the connectors thereof.

Connectors for electron discharge devices are frequently required to be flexible to allow for bending in the manufacture of the devices, as well as to allow for expansion and contraction during operation thereof. While flexible wire proves satisfactory for connectors in low power and relatively low frequency devices or tubes, under certain circumstances where said connectors perform additional functions or are used for ultra-high frequency operation and form part of lecher lines, it becomes desirable to use relatively rigid rods.

For example, in certain types of magnetrons, the connectors to the anodes serve as parts of lecher lines, support the anodes and in addition function as conduits for the cooling medium for said anodes. Flexible wire is unsatisfactory for a lecher line since it is difficult to maintain an accurate parallel relationship between two flexible wires; flexible wire makes a poor anode support since the wires give, particularly with temperature variations, and the anode is not maintained in fixed position; and finally flexible wire cannot readily serve as a conduit for a cooling medium. Under such circumstances, connectors are preferably made in relatively rigid form, such as for example, rigid rods, and openings are provided in said rods to convey the cooling medium.

While under said conditions the connectors are preferably relatively rigid, a certain amount of flexibility is desirable for the satisfactory manufacture of such devices and for their operation. In the manufacture of certain types of electron discharge devices (e. g. magnetrons) it becomes necessary to bend said rigid rods in sealing them to the envelope. Due to variations in the envelope which may be of glass, the particular bending of said rod may be in any one of a number of directions. If the connectors or rods do not have sufficient flexibility, they will exert strains and pressures upon the envelope which may ultimately result in the fracture of the envelope or the loosening of the seals. In the operation of many of such devices, particularly those utilizing a substantial amount of power, the temperature variations between operating and non-operating conditions may require that said rods accommodate substantial compression and expansion, which may be for example, a quarter inch variation in length. Furthermore where such rods or connectors additionally serve as lecher lines, as in the instances hereinabove cited, it is important that the means selected for rendering said connectors flexible, be such that there is no substantial change in the surge impedance of the

2

line and that no substantial additional impedances are introduced.

An object of the present invention is the provision of an improved flexible low impedance connector for electron discharge devices.

Another object is the provision of a connector of the type mentioned in the foregoing paragraph which further serves as part of a lecher line and which may also serve as a cooling medium conduit.

Other and further objects of the present invention will become apparent and the invention will be best understood from the following description of an embodiment thereof, reference being had to the drawings, in which:

Fig. 1 is a perspective view, partially broken away, of a connector embodying the present invention, supporting an anode of a magnetron;

Fig. 2 is a schematic, elevational view, partially broken away, of a magnetron employing connectors embodying the present invention; and

Fig. 3 is a view taken along the line 3—3 of Fig. 2.

Referring now to Fig. 1, the connector 1 for use in an electron discharge device is comprised of two relatively rigid portions 2 and 3 connected together by an intermediate portion 4. The relatively rigid portions 2 and 3 may be made of any suitable conducting material, such as copper, and may be in the form of rods. An anode 5 may be attached to rod 3 by any suitable means, such as for example, welding or brazing, and for the purpose of cooling the anode 5, rod 3 may be hollow so as to accommodate a cooling fluid. The intermediate portion 4 is made of conductive material which may be copper and is in the form of a tube whose opening or whose axis extends at right angles to the extension of rods 2 and 3. In the embodiment illustrated, the configuration of portion 4 is cylindrical having two extensions 6 and 7 at diametrically opposite points therefrom, which extensions fit into suitable slots 8 and 9 cut in the adjacent ends of the rods 2 and 3. The diameter of member 4 is preferably substantially equal to the diameter of either rods 2 and 3 and the length of the member 4 (measured horizontally) is preferably substantially the same as the diameter of either rods 2 or 3. Accordingly, portion 4 is aligned with rods 2 and 3 and does not project out therefrom to any material extent. The walls of member 4 are preferably sufficiently thin to permit rod 2 to move in various directions without requiring much force. The intermediate portion 4 introduces only a relatively low impedance in connector 1. When two such connectors are employed to form a lecher line, very little change in the surge impedance of the line is caused by the presence of intermediate

portions 4. The intermediate portion 4 may be made of a single flat ribbon doubled over on itself and bent to form both of the curved semi-cylindrical portions of the intermediate portion 4. It may also be made of two ribbons placed side by side and provided with semi-cylindrical bends, the ends of the two pieces fitting into the slots 8 and 9 respectively in rods 2 and 3.

Referring now to Fig. 2, in the magnetron 10 there illustrated, two such connectors 1 are employed, each having their rods 2 sealed through the upper end of the envelope 11 and their rods 3 sealed through the lower end of the envelope 11. Pipes 12 carrying the cooling fluid are inserted far into the opening in each of rods 3 and the cooling fluid flows out of pipes 12 into the space between said pipes 12 and rods 3. The anodes 5 supported on each of said connectors 1 are arranged opposite each other with a cathode 13 in the form of a single filament arranged in between. A magnetic field is provided by any suitable magnet (only indicated in the drawings by the word "magnet" and the numeral 14) which causes the electrons from the filament to move in a spiral path. To prevent the electrons emitted by cathode 13 from escaping between the anodes and hitting the walls of the envelope, (the envelope 11 being preferably made of glass and therefore susceptible to fracture due to the impact of the electrons thereon), shields 15 are arranged at the top and bottom of the anodes and additional shields 16 are mounted at the opposite ends of the anodes (see Fig. 3). The cathode 13 is mounted on supporting leads 17 extending out through the bottom of the envelope.

In the manufacture of the magnetron, the envelope consists of an upper and lower dished portion 18 and 19, respectively, which are brought together and fused along the line 20. Before this fusing, the lower dish-shaped member 19 has the rods 3 sealed therein. The upper dish-shaped member 19 is then brought over the rods 2. A sleeve 21 whose bottom 22 consists of Kovar, is slipped over each of the rods 2 and is brazed to rod 2 as well as sealed to the glass of the dish-shaped member 19. During these processes, the rod 2 is heated and therefore must have room for expansion. This is provided for by the intermediate member 4 in each of said rods which is readily-expandable as well as compressible. Furthermore, due to the shrinkage of the glass to which the sleeve 21 is sealed, a tilt may be given to rod 2, and rod 2 has to be able to bend with relationship to rod 3. This likewise is provided for by intermediate portion 4 which permits tilting of rod 2 in any given direction.

Likewise during operation of the magnetron, relatively large amounts of heat are developed, particularly where the magnetron handles a substantial amount of power. Under these circumstances it is particularly important that rods 2 and 3 be capable of expansion during operation and contraction after operation and cooling without putting too much strain upon the envelope or upon the seals.

While we have described above the principles of our invention in connection with specific apparatus, it is to be clearly understood that this description is made only by way of example and not as a limitation on the scope of our invention as set forth in the objects hereof.

We claim:

1. A connector for an electron discharge device comprising two relatively rigid portions and an intermediate connecting portion having a tubular

configuration with its axis substantially perpendicular to said rigid portions.

2. A connector according to claim 1 wherein said intermediate portion has two extensions each attached to one of said rigid portions.

3. A connector according to claim 1 wherein said intermediate portion has two relatively flat extensions, said rigid portions being slotted adjacent said extensions, said extensions being accommodated within said slots and attached within said slots to said rigid portions.

4. A connector according to claim 1 wherein said intermediate portion is substantially cylindrical and has two extensions at diametrically opposite points thereon, each attached to one of said rigid portions.

5. A connector according to claim 1 wherein one of said rigid portions is hollow and adapted to have a cooling medium circulated therein and 20 an electrode for said electron discharge device attached to said hollow portion and adapted to be cooled by said cooling medium.

6. A connector according to claim 1 wherein said intermediate connecting portion is substantially as long as the thickness of said rigid portions and is relatively thin to permit flexing thereof.

7. A connector according to claim 1, wherein said rigid portions are round rods having a diameter substantially equal to the length of said intermediate connecting portion and said intermediate connecting portion is substantially cylindrical having a diameter substantially equal to the diameter of said rigid rods.

35 8. In an electron discharge device including an envelope, and a connector according to claim 1, wherein said rigid portions are supported from said envelope and an electrode is mounted on one of said rigid portions and supported thereby.

40 9. In an electron discharge device including an envelope, and a connector according to claim 1, wherein said rigid portions are supported from said envelope, one of said rigid portions extending through the envelope and having an opening 45 extending lengthwise therein for the circulation of a cooling medium therethrough, an anode mounted on the rigid portion having an opening therein and adapted to be cooled by the cooling medium circulating therethrough.

50 10. In a magnetron having an envelope, a pair of connectors each comprising two relatively rigid portions and an intermediate connecting portion having a tubular configuration with its axis substantially perpendicular to said other portions, 55 said rigid portions being supported from said envelope, one of the rigid portions of each connector being hollow for the circulation of a cooling medium therethrough, a pair of anodes each mounted on one of said hollow portions and 60 adapted to be cooled by the cooling medium circulated therein.

11. A magnetron according to claim 10 wherein said intermediate connecting portion is relatively thin and the length of said tubular portion is substantially equal to the thickness of said rigid portions.

12. A magnetron according to claim 10 wherein said rigid portions are cylindrical and said connecting portion has a tubular configuration as long as the diameter of said rigid portions, said connecting portion and rigid portions being substantially aligned.
